United States Patent Office

Des. 191,686
Patented Oct. 31, 1961

191,686

PORTABLE GAS-HEATED FOG GENERATOR FOR DISPENSING INSECTICIDES OR THE LIKE

Harold D. Johnson and Robert W. Johnson, Clearwater,
Fla., assignors to General Implement Corporation,
Clearwater, Fla., a corporation of Florida

Filed Sept. 16, 1960, Ser. No. 62,167

Term of patent 14 years

(Cl. D62—2)

FIG. 1 is a side elevational view of a portable gas-heated fog generator for dispensing insecticides or the like embodying our new design;

FIG. 2 is a rear elevational view thereof; and

FIG. 3 is a perspective view thereof.

We claim:

The ornamental design for a portable gas-heated fog generator for dispensing insecticides or the like, as shown.
